UNITED STATES PATENT OFFICE.

GEORGE L. RICE, OF CHICAGO, ILLINOIS, ASSIGNOR TO INTERNATIONAL HARVESTER COMPANY, A CORPORATION OF NEW JERSEY.

TWINE BALL.

1,340,254.

Specification of Letters Patent. Patented May 18, 1920.

Application filed February 24, 1919. Serial No. 278,705.

To all whom it may concern:

Be it known that I, GEORGE L. RICE, a citizen of the United States, residing at Chicago, in the county of Cook and State of Illinois, have invented certain new and useful Improvements in Twine Balls, of which the following is a full, clear, and exact specification.

This invention relates to twine balls and 10 to methods of stacking twine balls to form a package of twine for shipment.

One object of the invention is to provide a ball of twine containing a maximum amount of twine in a given space, and a ball 15 of such formation that it will resist lateral strains which tend to cause it to collapse.

Another object is to provide a ball of such a nature that all of the twine comprising the ball may be unwound therefrom without 20 snarling.

A further object is to provide a ball so wound that it may be combined with, or stacked with, other balls having similar winding, in such a manner that the cubical 25 space occupied by the balls so stacked is reduced to a minimum.

A further object is to provide a ball of such formation that it may be readily combined with other balls of the same formation 30 to make a package in which the balls will resist lateral displacement.

And a still further object is to provide a method of so packaging twine balls of the particular formation specified that the cubical 35 space occupied by the balls is reduced to a minimum and the balls are firmly positioned against lateral displacement.

These objects are attained by forming a twine ball having an outer winding provided with outwardly projecting end portions 40 so formed that one end portion of each ball differs in size from the opposite end portion of the same ball, whereby the larger end portion of one ball may be stacked 45 against the smaller end portion of the adjacent ball, thus conserving space by nesting the end portion of the balls and also insuring the balls against lateral displacement.

More specifically stated, the objects are 50 attained in the present instance by forming a twine ball having a cover winding made up of a plurality of turns, the opposite ends of each of the individual turns being tan-

gential to circles of different diameters, thereby forming end portions for the balls 55 of different size.

The method, more specifically stated, consists of stacking the balls so formed in such a way that the end turns of the cover portion of one ball which are tangential to a circle of one diameter, will be positioned adjacent the end turns of the cover portion of another ball, which are tangential to a circle of different diameter. This results in the nesting of the end portions of the balls. 65

I have illustrated in the accompanying drawings one embodiment of my invention and in these drawings,—

Figure 1 is a side elevational view partly broken away showing two twine balls and 70 the cover windings of these balls, the balls being shown in stacked position;

Fig. 2 is a plan view of one end of the improved twine ball;

Fig. 3 is a plan view of the opposite end 75 of the ball; and

Fig. 4 is an elevational view of a package of twine balls, a portion of the package being broken away to show the method of stacking the balls. 80

In the embodiment of the invention shown, the particular features of the invention have been illustrated in connection with what is known as the cover winding of a twine ball, although it is not necessary that 85 these features be limited to the cover winding. The inner or main winding illustrated in the drawings is the well known type of universal winding such as illustrated in Patent No. 480,158 to S. W. Wardwell, Jr., dated August 2, 1892, and this winding need not be described in detail. The inner winding is close or compact and contains a maximum amount of twine for the space occupied, and for this reason this form of winding or some similar form is utilized for the 90 main winding.

As is well known, the main winding is formed by means of spiral turns of twine which run back and forth with respect to the 100 length of the ball. Upon the completion of this part of the ball which consists of a cylindrical body 10, there are left of necessity projecting portions 11 comprising the outer turns of the twine, and these portions in unwinding have given considerable trouble 105

from snarling and collapsing. To support these outer turns and also to prevent the longitudinal bulging of the ball due to lateral pressure, I have provided in the present instance an outer layer 12 which is tightly wound around the inner ball 10 and is preferably of the open formation illustrated in the drawings. As shown in Fig. 1, the end walls 13 of the cylindrical 10 are flat, and the end portions of the cover winding 12 fit closely against these flat ends. The outer surfaces of the ends of the cover winding are inclined with respect to the flat ends of the main winding, as shown at 14, and have a truss action whereby the ends of the outer cover exert an inward pressure on the flat ends of the main portion 10 of the ball. This inward pressure has a material effect in resisting tendency of the inner ball 20 to bulge when the ball is subjected to lateral pressure.

As illustrated in Figs. 2 and 3, the opposite ends of each of the individual turns of the cover winding are tangential to circles of different diameters, the ends of the turns at one end of the ball being tangential to a circle having a smaller diameter than the ends of the turns at the opposite end of the ball. This provides an uncovered area at 30 each end of the body 10, one of greater diameter than the other and both of greater diameter than the axial opening in the body, with the turns of the cover winding 12 banked around the margins of the uncovered area as best shown in Fig. 1.

The showing in Fig. 1 of one ball stacked upon the top of another ball, illustrates the positions of the end portions of the cover windings of two adjacent balls when these 40 balls are stacked for shipping. In this figure it will be seen that the larger uncovered area of one ball is positioned adjacent the smaller uncovered area of the other ball, the end turns which are banked or bunched at 45 the thickest portion of the winding of one ball being positioned over the thinner portion of the end of the adjacent ball. Thus the end portions of the adjacent balls are nested and the balls are so stacked as to resist lateral pressure.

From the above description of the construction of the balls and also of the showing in Fig. 1, it is believed that the method of stacking the balls will be clear, but this 55 method may be described briefly as follows:

After forming a plurality of balls having end portions of the construction illustrated and described, namely, balls having end portions of different size, the balls are stacked 60 one on top of the other in such a manner that the small end of one ball is positioned within the large end of the adjacent ball and after a sufficient quantity of balls have been so stacked the package of balls is wrapped in 65 any desired manner, as with burlap, and the

balls are securely tied together in the position in which they are stacked. This package construction is clearly illustrated in Fig. 4 of the drawings.

It will be readily seen that the package so 70 formed has great firmness and that the balls will resist any relative lateral displacement. It will be also seen that by nesting the balls in the manner described, the cubical contents of the package has been reduced to a 75 minimum, and this feature is of great importance when the packages are to be shipped.

While I have in the above specification described one embodiment of my invention, it 80 should be understood that the invention is capable of modification, and that modifications may be made without departing from the spirit and scope of the invention as expressed in the following claims:

1. An article of manufacture comprising a ball of twine having a cylindrical body and a cover winding thereon which leaves differing circular areas at each end of the ball uncovered, the opposite turns of each 90 of the individual windings of said cover being tangential to said areas.

2. An article of manufacture comprising a ball of twine, having a cylindrical body and a cover winding thereon which leaves 95 differing circular areas at each end of the ball uncovered, said turns forming ends for said cover winding of trussed formation, and the opposite turns of each of the individual windings of said cover being tangential to said areas.

3. An article of manufacture comprising a ball of twine comprising a cylindrical body having wound portions of different descriptions including an inner closely wound 105 portion having flat ends and an outer cover portion tightly embracing said inner portion and leaving openings of differing diameters exposing the inner portion at each end, the opposite ends of each of the individual windings of said cover portion being tangential to said openings.

4. An article of manufacture, a ball of twine consisting of a cylindrical body formed with an axial opening of substantially uniform diameter and having a cover winding formed to leave an uncovered area at each end of the body around said axial opening, with one uncovered area larger than the other.

5. An article of manufacture, a ball of twine consisting of a cylindrical body formed with flat ends and an axial opening, and a cover winding thereon formed to leave an uncovered area at each end of the 125 body of greater diameter than said opening and with one area of greater diameter than the other, the turns of the cover winding being thickly banked around the margins of said areas and becoming thinner toward the 130

edges of the body, whereby the end having the smaller uncovered area is adapted to nest with its central portion in the depression of the larger area on another ball.

5 6. The method of forming a twine package which consists of forming balls with opposite end portions of different size, and in stacking the balls so formed with the larger end of one of the balls adjacent to 10 and nested with the smaller end of the adjacent ball.

7. The method of forming a twine package which consists of forming balls with cover windings having a plurality of turns, 15 the opposite turns of the individual windings being tangential to circles of different diameters exposing each end of the ball, and of stacking the balls with the end of one ball having a circle of one diameter adjacent

the end of another ball having a circle of 20 different diameter.

8. The method of forming a twine package which consists of forming balls with windings provided with end portions tapering in thickness from the central portion of the ball outwardly, the thickest portion of the cover winding at one end of the ball being located a different distance from the center of the ball from the thickest portion at the opposite end of the ball, and of 25 30 stacking the balls with the end of one ball having its thickest portion a certain distance from the center adjacent the end of another ball having its thickest portion a different distance from the center. 35

In testimony whereof I affix my signature.

GEORGE L. RICE.
